UNITED STATES PATENT OFFICE.

EUGÈNE SCHNEIDER, OF LE CREUZOT, FRANCE.

AUTOMOBILE TORPEDO.

1,143,232.

Specification of Letters Patent. Patented June 15, 1915.

Application filed July 30, 1914. Serial No. 854,032.

To all whom it may concern:

Be it known that I, EUGÈNE SCHNEIDER, of Le Creuzot, France, have invented a new and useful Improvement in or Relating to 5 Automobile Torpedoes, which is fully set forth in the following specification.

In launching torpedoes from an above water or a submerged tube the propellers for some time are situated either in the air (in 10 the case of an above water tube) or in water and air (in the case of a submerged tube). In order to prevent the propellers from racing during this period, means have been provided for preventing the engine from 15 running at full speed until the propellers have completely penetrated the water. With this object the full admission of the working fluid to the engine has hitherto been retarded by reason of the fact that the opening 20 of the full admission valve is caused to depend upon the movement of a blade or shutter which is displaced by the impact of the water during the movement of the torpedo through the water. In this known 25 device the action of the water on the blade frequently does not take place properly and is frequently insufficient to overcome the inertia of the parts and the various resistances due to friction; furthermore the time during 30 which the engine runs at a low speed prior to the opening of the full admission valve, cannot be regulated in a precise and adjustable manner.

The chief object of the present invention 35 is to provide a device which will overcome the above mentioned defects.

According to this invention the element 40 that retards the operation of the full admission valve, instead of being dependent upon a device actuated by the water, is connected with the engine of the torpedo by a mechanism which is clutched into connection with the engine and is declutched at the end of 45 a certain number of revolutions of the shaft of the engine, this number being capable of regulation at will. The member that effects the operation of the full admission valve may be constituted by a push rod connected with the usual balance lever that controls 50 the stopping mechanism of the engine. The mechanism connecting the push rod to the shaft of the engine is constituted by a clutch similar to the clutch of the said stopping mechanism.

Figure 1 of the accompanying drawing 55 illustrates diagrammatically the installation

hitherto adopted in which the movement of the full admission valve is dependent upon the movement of a member actuated by the water. This installation comprises the usual balance lever B connected at Z by a rod B' 60 with the starting lever L. At one of the extremities of this balance lever, the finger B² of the known stopping mechanism is pivoted. This mechanism (which is shown 65 in detail in Fig. 2) comprises a clutch C C', the member C' rotated by the motor being subjected to the action of a spring R. When the lever L is depressed, the clutch member C is displaced by the finger B² the movement 70 of the member C compressing the spring R. By means of a lever N a reduced admission valve K is controlled by the lever L; as is known the lifting of this valve enables the motor to run at low speed while at 75 the same time it insures the operation of the gyroscope. A push rod b is also pivoted to the balance lever B and serves to control the full admission valve A—a, which is in the form of a differential valve. The movement 80 of the push rod b which is produced by the action of the spring R, is first of all prevented by the striking of a member I against a stop H which can only be moved aside by the action of the water upon a tail 85 piece constituting a blade. This known arrangement possesses the defects enumerated above.

In order that my invention may be clearly understood and readily carried into effect 90 I will describe the same more fully with reference to Figs. 2 and 3 of the accompanying drawings, Fig. 2 being a general sectional elevation and Fig. 3 a partial plan of a constructional form of the invention. 95

In Figs. 2 and 3 as in Fig. 1, L designates the starting lever which is connected by the rod B' with the usual balance lever B which, by means of the finger B² controls the known stopping mechanism C—C'. b designates 100 the push rod operating the differential full-admission valve A—a. N—Q is the member for actuating the reduced admission valve K. I designates a member which moves with the balance lever B and which 105 is guided in bearings J, J' rigid with the casing A'. A spring r bearing at one end upon a ring M fixed to the member I and at the other end upon a fixed stop formed by the bearing J, constantly tends to return 110 the member I to the position represented in Fig. 2.

2

In accordance with the invention, the full movement of the member I is dependent upon a clutching and declutching mechanism actuated by the shaft of the engine. 5 This mechanism may as shown be similar to the known stopping mechanism. In a casting E, which may be integral with the casting A' a clutch member F is capable of rotating. The other clutch member H is 10 provided with a tailpiece carrying at its upper extremity an indicating hand H' which is displaceable over a graduated dial H² by means of a stop H³ carried by a ring H⁴. Around the rod carrying the clutch 15 member H a torsion spring r' is coiled; one end of this spring is fixed to the member H and the other to a ring H⁴ pressed into the dial H² by a powerful spring H⁵. The member F is provided externally with teeth 20 by means of which it gears with a pinion F' keyed to a shaft G driven by the engine.

The operation of the mechanism is as follows:—If it be desired to retard the full admission of motive fluid that is to say the 25 opening of the valve A—a, in such a manner that it takes place only at the end of a certain number of revolutions of the shaft of the engine the hand H', is brought opposite the scale division on the dial H² corresponding 30 to this number of revolutions. As a result an orifice h in the member H assumes an angular position relatively to the rod I corresponding to this scale division. When, on starting, the lever L is turned downward 35 and caused to occupy the position L' (Fig. 2) the part Q is raised by the lever N and opens the reduced admission valve K. At the same time the member F rotates under the influence of the pinion F'. The movement 40 of the lever L causes the member I to strike against the member H which is thereby clutched to the member F. The travel of the balance lever B is insufficient to then produce the lift of the valve A by the push 45 rod b. The clutch member F drives the member H. When the motor has effected the predetermined number of revolutions, the hand H' returns to zero. At the same time the orifice h comes opposite the member I which enters it. The clutch member 50 H is then no longer pressed against the member F and consequently it no longer participates in the rotary movements of the member F. The spring r' facilitates the 55 separation of the two clutch members H F. The penetration of the finger I into the orifice h has enabled the member b to effect its full lift so that the valve A—a is opened. It will be noted that this lift is insured at 60 the end of a number of revolutions of the motor which can be regulated at will.

The starting lever L is as is known maintained in the position L' by a locking device which is released when the stopping mechanism acts, thereby insuring the return of the 65

lever from the position L' to the position L under the influence of a spring which is not shown. As a result of this return the balance lever B is depressed and returns the members Q b and I to their initial positions 70 as shown in Fig. 2. The two valves K and A—a close and the clutch member and the hand H' return to the selected position of adjustment under the influence of the torsion spring e which was energized during 75 the rotation of the clutch member H.

What I claim and desire to secure by Letters Patent of the United States is:

1. A device for retarding the admission of working fluid to the engine of a torpedo, 80 comprising a fluid admission valve, means normally restrained from acting on said valve to open the same, and means adapted to be operated by the engine for releasing the valve actuating means after a predetermined number of revolutions of the engine. 85

2. A device for retarding the admission of working fluid to the engine of a torpedo, comprising a fluid admission valve, a push rod for opening said valve, and a clutch device one member of which has driving connections with the engine and means connected with said rod and in the path of the companion clutch member for restraining movement of said push rod during engagement of said clutch members and released by said companion member after a predetermined number of revolutions of the engine. 95

3. A device for retarding the admission 100 of working fluid to the engine of a torpedo, comprising a fluid admission valve, a push rod for opening said valve, a clutch device having two clutch members, one of which has driving connections with the engine, 105 and the other provided with a recess, a spring-pressed rod connected with said push rod and in the path of the said other clutch member to restrain movement of said push rod during engagement of said clutch members, and released for opening said valve when a predetermined number of revolutions 110 of the engine brings said opening opposite the end of said spring-pressed rod to release the clutch. 115

4. A device for retarding the admission of working fluid to the engine of a torpedo, comprising a fluid admission valve, a push rod for opening said valve, a clutch device having two clutch members one of which 120 has driving connections with the engine and the other provided with an opening and means for angularly displacing said member to set said device, a spring-pressed rod connected with said push rod and in the path of said other clutch member to restrain movement of said push rod during engagement of said clutch members, and released for opening said valve when a predetermined number of revolutions of the engine 125

brings said opening opposite the end of said spring-pressed rod to release the clutch.

5. In a fluid admission device for automobile torpedo engines, the combination of a low speed fuel admission valve and a high speed fuel admission valve adapted to operate in succession, normally restrained operating means for the last-named valve, and engine driven means adapted to release said

valve operating means after a predetermined 10 number of revolutions of the engine shaft.

In testimony whereof I have signed this specification in the presence of two subscribing witnesses.

EUGÈNE SCHNEIDER.
